DESIGN.

H. C. BASCOM.
HEATING STOVE.

No. 20,465.

Patented Jan. 6, 1891.

UNITED STATES PATENT OFFICE.

HENRY CLAY BASCOM, OF LANSINGBURG, NEW YORK.

DESIGN FOR A HEATING-STOVE.

SPECIFICATION forming part of Design No. 20,465, dated January 6, 1891.

Application filed December 3, 1890. Serial No. 373,492. Term of patent 3½ years.

To all whom it may concern:

Be it known that I, HENRY CLAY BASCOM, a citizen of the United States, residing in the village of Lansingburg, in the county of Rensselaer and State of New York, have invented and produced a new and original Design for Heating-Stoves, of which the following is a specification, reference being had to the accompanying photograph of a stove having my said design.

This design embraces the ornamented legged support A, the ornamented stove-body embracing the base B, lower section having the corner pilasters C and end panels D, the mid-flange E, the upper section having the corner pilasters C' and end panels D' and the projecting top F, the top dome G, the removable upper front panel H, the detachable lower front panel I, and the lower front door J.

The design for the legged support A consists, essentially, of its quadrilateral and convexly-curved shape and the central foliated mask a, with lateral scrolls b, and the foliate scroll-vine corner ornaments c on the sides of said support.

The design of the stove-body embraces the quadrilateral projecting base B, having the scalloped molding d, the corner pilasters C C', having the curved crossing bands and foliate scroll ornamentalations e e', the raised and convexly-curved end panels D D', the quadrilateral molded mid-flange E, and the quadrangular projecting molded top F.

The design for the top dome G consists of its quadrilateral and angular upwardly-tapering arched shape with the compound scroll-leaf ornament f and the combined foliate scroll-vine ornamentalations g h, shaped and disposed in harmony with the other ornamentalations of the stove.

The ornamental design of the lower and upper end panels D D' consists of the basal scroll-leaf ornament i and the compound over-arching foliated vine-like scroll-band ornamentation j on said lower panel, and the scroll-leaf ornament i', and over-arching foliated vine-like scroll-band ornamentation k on said upper panel.

The ornamental design of the oblong rectangular upper front panel H consists, essentially, of the central rosette l and the later-

ally-extending, curved, and crossing foliate vine-like scroll-bands m.

The ornamental design of the oblong rectangular front panel I consists, essentially, of the central rosette n and the laterally-extending, curved, and crossing foliate vine-like scroll-bands o.

The design for the lower front door J consists of its molded projecting lower part p and the main upright portion having in open-work form the compound curved and crossing foliate vine-like scroll-bands r and s.

I claim as new—

1. The design for a heating-stove, comprising the legged support, the stove-body, the top dome, and the panels and front door on the stove-body, all shaped and ornamented substantially as shown and described.

2. In a design for a stove, the design for the legged support, comprising its quadrilateral and convexly-curved shape and a central foliated mask with side scrolls and foliate scroll-vine corner ornaments, as shown and described.

3. In a design for a stove, the design for the stove-body, embracing the quadrilateral base with a scalloped molding thereon, the lower and upper corner pilasters having curved and crossing ornamental bands and foliate ornaments, the lower and upper raised and convexly-curved end panels, the quadrilateral molded mid-flange, and the projecting quadrangular molded top, as shown and described.

4. In a design for a heating-stove, the design for the top dome, consisting of its quadrilateral and angular upwardly-tapering arched form and the combined scroll-leaf and foliated scroll-vine ornamentalations on said dome, as shown and described.

5. In a design for a stove, the ornamental design of the lower and upper raised and convexly-curved end panels, the same consisting of the two distinct basal scroll-leaf ornaments and the two distinct and different over-arching foliated vine-like scroll-band ornamentalations on said panels, as shown and specified.

6. In a design for a stove, the ornamental design for the oblong rectangular upper front panel, consisting of the central rosette and the laterally-extending, curved, and crossing

foliated vine-like scroll-bands, substantially as shown and described.

7. In a design for a stove, the ornamental design of the oblong rectangular lower front panel, consisting of the central rosette and the laterally-extending, curved, and crossing foliated vine-like scroll-bands, as shown and described.

8. In a design for a stove, the design of the lower front door, the same consisting of its projecting molded lower part and the main

upright portion having in open-work form the compound curved and crossing foliated vine-like scroll-bands, as shown and described.

In testimony whereof I hereunto set my hand, in the presence of two subscribing witnesses, this 1st day of December, 1890.

H. CLAY BASCOM.

Witnesses:

CHARLES H. BENEDICT,
CHESTER BASCOM.
